UNITED STATES PATENT OFFICE

THOMAS F. QUIGLEY, OF CLEVELAND, OHIO, ASSIGNOR TO MICROMATIC HONE CORPORATION, A CORPORATION OF MICHIGAN

HYDRAULIC HONING AND LAPPING MACHINE

Application filed February 23, 1928. Serial No. 256,244.

This invention has to do with the art of finishing engine cylinders and similar hollow bodies wherein smooth accurately dimensioned surfaces are necessary in view of 5 the necessity of fitting into such bodies, pistons or like members requiring exceedingly close and accurate fitting in operation. Means for the purpose stated are commonly known as lapping heads or hones and are 10 primarily useful for grinding and polishing the surfaces operated upon, with remarkable accuracy.

The improvements of this invention are primarily to the type of hones or laps for engine cylinder grinding purposes wherein there is employed a head at the exterior of which are mounted abrading devices, instrumentalities being arranged within the head for controlling the adjustment of the abrading 15 members to the required nicety effective for the grinding and finishing operation of the hollow body with which the tool of the invention is used.

It is highly desirable in a tool of the 20 class described, that the abrading members which perform the grinding and finishing function shall be positively held in expanded positions for their effective action upon the work, and that these members shall be capable of such pivotal or tilting and radial adjustment as to be expanded by equal or unequal movements outward of their opposite ends for proper action upon the cylinder 25 wall, or wall of whatever body is being finished, and in order that the abrading surfaces of the abrading members may be set in parallelism with the wall or work in process of being finished.

In the operation of tools of the class 30 described, owing to conditions of service, it is not uncommon that the abrading surfaces of the abrading members are somewhat more greatly worn at one or corresponding ends 35 than at the other ends, and for effective utility, it is highly desirable and necessary that the means for expanding the abrading members shall enable their surfaces to be adjusted in parallelism with the work operated on 40 throughout the grinding and finishing oper-

ation. By this invention such adjustment is manually accomplished.

To the end of obtaining a highly efficient tool for the purposes described, I utilize independently movable expanding elements 55 mounted within a bore in the head, each element serving as an inner cam element coacting with a set of outer cam elements upon the adjacent corresponding ends of externally mounted shoes for abrading members. I further utilize operating means whereby to effect independent movement of said independently acting expanding elements so that 60 each of these elements may be moved, irrespective of whether the other element is moved or not, the movements of the elements for expanding the abrading members at either end or at both ends being controlled by the said operating device or means, which coacts with both of the expanding elements 65 and is preferably under manual control. In the carrying out of my invention, I contemplate use of an operating device which 70 is hydraulic in its character consisting of a piston capable of acting upon a liquid of greater or less viscosity disposed in the hollow portion of the head carrying the abrading members, or an extension thereof, the action of the piston being to force the fluid 75 medium operated on thereby so that the latter exerts a pressure force against the abrading member expanding elements, which force 80 may act independently thereon so that these elements may perform their expanding functions independently of one another, by the 85 manual control provided therefor.

I have embodied my invention in the hydraulic type of lapping head or hone illustrated in the accompanying drawings, in 90 which:—

Figure 1 is a vertical section through the grinding tool and driving instrumentalities.

Figure 2 is a transverse section through the head and abrading members.

Figure 3 is a transverse section through the universal joint taken about on the line 3—3 of Figure 1.

Figure 4 is a transverse section through the connection between the head and driving 100

mechanism taken about on the line 4—4 of Figure 1.

Figure 5 is a detail showing of the bayonet joint between the driving means and head.

5 Figure 6 is an enlarged detailed view, partly in section, of a portion of the slot connection.

Figure 7 is a fragmentary showing of an abrasive member mounted in the head, bringing out more particularly the circumferential groove in the head receiving pins on the abrasive members.

10 Figure 8 is a fragmentary view in transverse section of the pin connection between an abrading member and the head.

15 Figure 9 is a detail fragmentary showing of a portion of the braking instrumentalities.

Figure 10 is a side view of the driving and braking instrumentalities associated therewith, parts being removed to more clearly bring out the construction of other parts.

20 Figure 11 is a view somewhat diagrammatic of the adjustable stop means.

Figure 12 is a view partly associated bringing out the construction of the planetary gearing.

25 Figure 13 is a side view somewhat diagrammatic of the universal joint between the two portions of the head.

30 Figure 14 is a view in side elevation, somewhat fragmentary, of the braking instrumentalities.

Figure 15 is a detail showing of a portion of the braking means.

35 Describing my invention in detail, in conjunction with the drawings, I provide a head or cylindrical body 1 having a hollow formation to afford a passage or bore 2 through said head. The head is made in two sections, the

40 lower section generally designated 1 and the upper section generally designated at 1a, these parts being connected together by universal joint means consisting of a collar 3 having diametrically opposite screws 4 en-

45 gaging the main body 1 of the head at opposite sides, and having other diametrically opposite screws 4a engaging extensions 1b of the upper section 1a of the head, the collar being loose around the parts and providing

50 the universal coupling connection referred to.

A retainer ring 5 of resilient formation encircles the collar or ring 3, and engages the various screws to prevent loosening the same up due to vibration or other causes under 55 actual service conditions. Ends of the retainer member 5 are interlocked with the collar 3 by extensions at such ends engaging in recesses in the collar at points designated 6.

It will be observed that the main section or 60 head 1 projects at its upper portion into the lower tubular portion of the section 1a and is equipped with a removable end piece 7 held in place by screws 8 and through which passes a screw rod 9 having a swiveled connection at its lower end at 10 with a plunger

11. In order to enable a liquid such as oil or grease or other fluid serving for a transmission of pressure to be inserted in the head 1 in the space beneath the plunger 11, (said space providing a chamber that may be continuous with the mentioned bore 2) a removable plug 12 is mounted in a side of said head to normally close the inlet opening thus provided. The plug 12 may be a pressure fitting such as known in the art as an Alemite fitting to enable grease or oil to be readily supplied to the chamber designated 13 without the removal of the plug or fitting, this being immaterial to the invention.

80 Within the head 1 are mounted the independently acting expanding elements 14 and 15 which are preferably cones in specific formation. These inner cam elements are shown as facing in the same direction, the cone 14 having an extension body 14a forming a piston closely fitting against the inner wall of the head 1 and the parts 14 and 14a being provided with an opening or bore concentric therewith. In the bore of the expanding element 14 and its body 14a there may be mounted a secondary piston 16, shown as carried by a stem or rod 17 that extends below the expanding element 14 and has a pinned connection at 18 with the expanding element 15, the body of which above the cone shaped portion, fits snugly in the hollow bore 2 of the head 1.

85 Abrading members or shoes are mounted at the exterior surface of the head 1 and embody the carriers 19 and the abrading blocks 20. These may be of a known type, generally speaking, and may be equipped with pins 21, arranged in separate sets and serving as outer cam elements, loosely projecting inwardly therefrom and passing through radial openings in the head 1 so as to project within the hollow portion of said head and engage with the expanding or inner cam elements 14 and 15. Springs 22 are shown as utilized to hold the abrading members upon the head under contracting tension of the springs thereby acting to maintain the pins 21 engaged at their inner ends with the expanding surfaces of the expanding members 14 and 15.

90 The head 1 is formed with longitudinal grooves 23 in which the carriers 19 of the abrading members are seated with a fair degree of snugness permitting movement thereof, however, under expansive or contractive forces. Intermediate of their ends, the abrading members are formed with cross pins 24 that are seated in open grooves or recesses at right angles to the main grooves 23, the purpose of these cross pins being to prevent longitudinal displacement of the abrading members from the positions of their mounting upon the head 1, while permitting radial or tilting movement thereof. A single annular groove encircling the head 1 will be provided for the various pins as the most 95

convenient method of forming the seats for said pins 24.

With the foregoing features of construction of my tool in mind, I preferably obtain the desirable operation incident to the action of the plunger 11 downward in the chamber 13, as follows: The plunger operates to, apply pressure upon the liquid in the chamber 13, said liquid, or its equivalent, serving to transmit pressure to the pressure sides of the pistons 14a and 16 that control the movements of the expanding elements 14 and 15. This pressure is preferably obtained and varied by manual operation of the plunger 11 by means later to be described and when said pressure is exerted upon the expanding elements, the movement of the latter is transmitted to the abrading members 19 to move outward either end of these members according to which one of the elements 14 or 15 is actuated. Owing to the independent action of the parts 14 and 15, respectively engaging an upper or inner set and a lower or outer set of pins 21, shown as having their ends so rounded as to enable them to function in spite of some longitudinal tilting of shoes 19, to correct a pressure differential. It is obvious that wear upon either end of the abrasive surface of the abrading members may be compensated for by the expansion of such end. Moreover, by the movement of the plunger 11, the opposite ends of the abrading members may be independently adjusted at all times under manual control to maintain the abrading surfaces of the shoes 19 parallel with one another, and parallel with the walls or surfaces of the working contact with which the abrading members are operating. The plunger 11 (shown as movable in a chamber continuous with bore 2) or other means used to apply the pressure of an identical volume of fluid to the pistons 14a and 16, shown as concentric, may be equipped with any suitable packing discs or cups as will be obvious. The upward limit of movement of the parts 14 and 15 is controlled by a removable screw stop 25.

The preferred operating means for the plunger 11 as illustrated, forms the subject matter of a separate application for patent which may be briefly set forth.

The screw threaded rod 9 terminates in a square shank 26 that projects into a sleeve 27. The sleeve 27 is detachably connected with the head 1a by a pin and slot connection of the bayonet type as shown at 28. The sleeve 27 carries a main body member 29 having recesses therein, in which are located gears 30 and 31. The gear 30 has bearing in bushings 32 while gear 31 rotates on a pin 33 journaled in recesses in the member 29. A large internal ring gear 34 is carried by a sleeve 35 and is meshed with the gear 31 that in turn engages the gear wheel 30 that receives the square shank 26. The shank 26

terminates in a concavity within a shank 36, adapted for connection to a suitable driving means. Under normal conditions, rotation of the shank 36 causes rotation of all the parts comprising sleeve 35, head 29, sleeve 27 and head 1a without any functioning of the gears. However, upon application of the brake means shown at 37 which includes a friction band 38, the rotation of the sleeve 35 is stopped, which sets into operation gears 34, 30 and 31 to cause operative rotation of the threaded rod 9. To limit the rotation of the gears in the manner previously described, the sleeve 35 is provided with a stop 39, while collar 40 carried by shank 36 is provided with a complementary stop 41. When the stop 39 abuts the stop 41, operative rotation of the gears is prevented. The position of stop 41 may be varied by ratchet mechanism 42 comprising teeth 43 and dog 44. This mechanism determines to just what extent the plunger 11 is forced into the chamber 13.

Ratchet teeth 43 are formed on ring 45, while dog 44 is pivoted at 46 to the ring member 40. The rings 45 and 40 are maintained in proper relation by a collar 47.

The bayonet slot connection 28 and 29 between the head 1a and sleeve 27, is positively maintained or locked by a locking detent 48 actuated by a leaf spring 49 fastened to the interior of the head 1a by a screw 50. This locking detent prevents relative rotation between the parts 1a and 27 thereby limiting the possibility of an accidental disconnection of these parts.

Braking instrumentalities 37 and 38 comprise more particularly, the band 37 broken at 51 to provide ears 52 which are connected together by a screw bolt 53. The screw bolt 53 carries a cam actuating member 54, which has a cam surface that cooperates with a cam surface 55 on one of the ears 52. Upward movement of the actuating member 54 through the medium of the cam surface thereon and cam 55, tightens the band 37 around sleeve 35 to prevent rotation thereof, when the operation of the tool demands such action. Nuts 56 maintain the assembly of the parts 54, 52 and 53.

Having thus described my invention, what I claim as new and desire to secure by Letters Patent of the United States, is:—

1. In a honing or lapping tool of the class described, in combination, a head, a plurality of abrading members carried by said head, expanding elements cooperative with opposite ends of the abrading members, and means connecting these elements for separate movement to maintain the expanding elements in positions positively holding the abrading members to their work, said means allowing the expanding members to move relative to each other during the abrading operations.

2. In a honing or lapping tool of the class described, in combination, a head, a plural-

- ity of abrading members carried by said head, expanding elements cooperative with opposite ends of the abrading members, means connecting these elements for separate movement with means for maintaining the expanding elements in positions positively holding the abrading members to their work, and a single means for acting upon the expanding elements, said last named means permitting movement of the expanding members relative to each other during abrading operations.
3. In a honing or lapping tool of the class described, in combination, a head, a plurality of abrading members carried by said head, and independently operating expanding elements cooperative with opposite ends of the abrading members, with means for maintaining the expanding elements in positions positively holding the abrading members to their work, and a single means for acting upon the independently operating expanding elements, one expanding element comprising a portion which operates through the other.
4. In a honing or lapping tool of the class described, in combination, a head, a plurality of abrading members carried by said head, and independently operating expanding elements cooperative with opposite ends of the abrading members, with means for maintaining the expanding elements in positions positively holding the abrading members to their work, a piston carried by each expanding element, and hydraulic means acting upon the pistons for applying expanding pressure thereto.
5. In a honing or lapping tool of the class described, in combination, a head, a plurality of abrading members carried by said head, and independently operating expanding elements cooperative with opposite ends of the abrading members, with means for maintaining the expanding elements in positions positively holding the abrading members to their work, a piston carried by each expanding element, and hydraulic means acting upon the pistons for applying expanding pressure thereto, and the said pistons being disposed in approximately the same plane.
6. In a honing or lapping tool of the class described, in combination, a head, a plurality of abrading members carried by said head, and independently operating expanding elements cooperative with opposite ends of the abrading members with means for maintaining the expanding elements in positions positively holding the abrading members to their work, coaxial pistons connected with the expanding elements and a plunger for acting upon a fluid pressure medium to apply the pressure of the latter to said pistons.
7. In a honing or lapping in tool of the class described, the combination of a head, a plurality of abrading members carried by the head, an expanding element in the head cooperative with corresponding ends of the abrading members, a separately movable expanding element in the head cooperative with the other corresponding ends of the abrading members, and operating devices connected with the expanding elements and operable to hold the abrading members positively against the work without yielding, so as to make a hole of uniform bore.
8. In a honing or lapping in tool of the class described, the combination of a head, a plurality of abrading members carried by the head, an expanding element in the head cooperative with corresponding ends of the abrading members, and a separately movable expanding element in the head cooperative with the other corresponding ends of the abrading members, the expanding elements being arranged so as to hold the abrading members positively against the work without yielding, and a single acting means acting upon the expanding elements to so hold the abrading members against the work though permitting the expanding members independent movement as specified.
9. A honing tool of the class described, comprising, in combination, a head, a plurality of abrading members carried by the head, independently operating expanding members cooperative with the abrading members, coaxial pistons extending from the expanding member and constituting operating means therefor, means for applying operative pressure on the pistons, and means for preventing relative longitudinal movement between the abrading members and the head.
10. A honing tool of the class described, comprising, in combination, a head, an abrading member carried by the head, independently operating actuating members cooperative with opposite ends of the abrading member to move the latter into parallelism with the work, piston means extending from the actuating members and extending into a fluid pressure chamber, the pistons being arranged to move the actuating members in the same operative direction, and a plunger for creating pressure on the fluid.
11. A honing tool of the class described, comprising, in combination, a head, a plurality of abrading members carried by the head and adjustable relative thereto, cam expanding members independently operable through opposite ends of the abrading members to expand the latter, said head having a fluid pressure chamber, means for exerting pressure on the fluid in the chamber, and instrumentalities for actuating the expanding members under pressure of the fluid.
12. In a tool of the general character described: a head provided with a longitudinal bore and with abrading shoes inwardly carrying, near the ends thereof, outer cam elements which extend, in separate sets, into said bore; independently movable inner cam ele-

- ments respectively engaging the cams of one of said sets; and hydraulic means, carried by said head, tending to position said inner cam element.
- 5 13. In a tool of the general character described: a head provided with a longitudinal bore and with abrading shoes inwardly carrying, near the ends thereof, outer cam elements which extend, in separate sets, into said bore; independently movable inner cam elements, 10 respectively engaging the cams of one of said sets; and hydraulic means carried by said head, tending independently so to position said inner cam elements as to compensate for inequality in the wear of said shoes.
- 15 14. In a tool of the general character described: a head provided with a longitudinal bore and with abrading shoes inwardly carrying, near the ends thereof, outer cam elements 20 which extend, in separate sets, into said bore; independently movable inner cam elements respectively engaging the cams of one of said sets; and hydraulic means, carried by said head, tending to position said inner cam elements,—said inner cam elements being carried by pistons which are concentrically related relatively to said bore.
- 25 15. In a tool of the general character described: a head provided with a longitudinal bore and with abrading shoes inwardly carrying, near the ends thereof, outer cam elements 30 which extend, in separate sets, into said bore; independently movable inner cam elements respectively engaging the cams of one of said sets; and hydraulic means carried by said head, tending to position said inner cam elements,—said inner cam elements being carried by pistons which are concentrically related relatively to said bore and are exposed 35 to the pressure of an identical volume of fluid.
- 40 16. In a tool of the general character described: a head provided with a longitudinal bore and with abrading shoes inwardly carrying, near the ends thereof, outer cam elements 45 which extend in separate sets, into said bore; independently movable inner cam elements respectively engaging the cams of one of said sets; and hydraulic means carried by said head, tending to position said inner cam elements,—a chamber being formed, continuous 50 with said bore, to receive fluid comprised in said hydraulic means.
- 55 17. In a tool of the general character described: a head provided with a longitudinal bore and with abrading shoes inwardly carrying, near the ends thereof, outer cam elements which extend, in separate sets, into said bore; independently movable inner cam elements 60 respectively engaging the cams of one of said sets; and hydraulic means, carried by said head, tending to position said inner cam elements,—a chamber being formed, continuous with said bore, to receive fluid comprised in 65 said hydraulic means and said chamber be- ing provided with means for varying the pressure on said fluid.
18. In a tool of the general character described: a head provided with a longitudinal bore and with abrading shoes inwardly carrying, near the ends thereof, outer cam elements which extend, in separate sets, into said bore; independently movable inner cam elements respectively engaging the cams of one of said sets; said inner cam elements being faced in the same direction; and means independently so advancing said inner cam elements as to compensate for unequal wear near the respective ends of said shoes by correction of a pressure differential.
- 70 75 80 85 90 95 100 105 110 115 120 125 130
19. In a tool of the general character described: a head provided with a longitudinal bore and with abrading shoes inwardly carrying, near the ends thereof, outer cam elements which extend, in separate sets, into said bore; independently movable inner cam elements respectively engaging the cams of one of said sets;—said head being provided with a peripheral groove, and said shoes being provided with pins so entering said groove as to hold said shoes against longitudinal movement while permitting a tilting movement thereof relatively to said head, an inner cam being advanced by means responsive to a pressure differential.
- In testimony whereof I affix my signature.
- THOMAS F. QUIGLEY.
